HUSKING ROLL

Oscar Lakin, Chicago, Ill., assignor to A. Lakin & Sons, Inc., Chicago, Ill., a corporation of Illinois

Application December 29, 1950, Serial No. 203,520

1 Claim. (Cl. 130—5)

1

This invention relates to improvements in corn husking rolls and refers particularly to a corn husking roll constructed of relatively flexible resilient material, said roll having a working surface of either continuous helices or discontinuous helices.

One of the features of my invention relates to corn husking rolls which may be constructed of waste material, such as, automobile tire casings, the rolls comprising a plurality of superimposed discs cut from said casings and carried upon a rigid core.

Another feature of my invention relates to an improved corn husking roll of the character described comprising discs whose peripheries are scalloped and whose centers are so related to a core of angular section that a helix, continuous or discontinuous, is formed by said scallops upon the surface of the roll.

A further important feature of my invention relates to a roll of the character described whose discs have chamfered or frustro-conical peripheral defining surfaces whereby a better purchase may be had upon the husks being passed in contact with a juxtaposed pair of said rolls.

Other objects, advantages and features of my invention will be apparent from the accompanying drawing and following detailed description.

In the drawing.

Fig. 1 is a transverse sectional view of my improved corn husking roll.

Fig. 2 is a fragmentary side elevational view of the roll, parts being broken away and parts being shown in section.

Fig. 3 is a fragmentary side elevational view of a modified form of corn husking roll.

Figs. 4, 5 and 6, are sequential sectional views illustrating adjacent discs of the roll shown in Fig. 3, the central apertures of said adjacent discs being angularly offset with respect to each other.

Fig. 7 is a fragmentary side elevational view of another modified form of corn husking roll.

Referring in detail to the drawing, 1 indicates a disc which comprises a component of corn husking roll 2. The disc 1 is constructed from a flexible, resilient material such as rubber or the like, said disc preferably being constructed of automobile tire casings or carcasses. The periphery of the disc 1 is provided with a plurality of scallops 3 which may be shaped, as shown, or may be made to conform to substantially any pattern which preferably repeats itself one or more times throughout the 360° angle of the disc.

The roll 2 is constructed from a rigid core 4, preferably metal of angular cross-section, upon which are mounted a plurality of discs 1. Each disc 1 is provided with a central aperture 5 which conforms with the transverse section of the core 4 whereby the discs may be disposed in plane-parallel, face-abutting relationship upon the core.

As a feature of the present form of my inven-

2

tion, the discs 1 upon the core are all identical with respect to the position of the central aperture 5 and the scallops 3, that is, the relationship between the position of the scallops and the sides and corners of the central aperture 5 are the same in all discs. Employing the discs 1 the core 4 is first twisted to permanently dispose the original angular section at increments in angularly offset relationship to form a plurality of 10 parallel helices upon the core surface. The discs 1 are then threaded upon the core to be disposed in plane-parallel, face-abutting relationship. In view of the fact that the discs are all identical, a plurality of helices are formed by the scallops 15 3 upon the outer surface of the roll 2. Of course, suitable end-securing means are provided to clamp the endmost discs adjacent the ends of the core, such as, for instance the clamping means shown in Siemen Patent 2,416,124, issued 20 February 18, 1947, to maintain the discs 1 in pressure contact with one another.

Referring particularly to Fig. 7, a core 6 similar to core 4 is employed and upon said core a plurality of discs 7 are mounted, discs 7 being 25 identical with the previously described discs 1. In this form of my invention, an alternate relationship between a group 8 of discs 7 is spaced from the next group 8 by a group 9 of discs 10. The discs 10 are of circular contour and are provided with central apertures similar to apertures 5. The discs 10 may be of smaller diameter than discs 7 or may be substantially the same in diameter. Of course, it is to be understood that the alternate arrangement of groups 8 and 9 proceeds throughout the length of the roll thus 30 formed and suitable end-clamping means (not shown) is also contemplated.

In the form of roll illustrated in Fig. 7, when 40 a pair of rolls are employed in juxtaposed relationship, as is usual in conventional corn husking machines, the groups 8 upon one roll may be staggered with respect to a similar group upon the opposed roll so as to bring the peripheries of discs 7 on one roll adjacent the peripheries of the discs 10 upon the opposed roll. Of course, 45 the manner in which the corn husking rolls herein are employed is not intended to limit my invention, since the invention is directed to the rolls per se regardless of the manner in which the rolls may be used or the purpose of use of the rolls.

Referring in detail to Figs. 3, 4, 5 and 6 another modification of my invention is shown. In this 55 form of my invention the surface of the roll may be similar to the roll shown in Fig. 7, but the relationship of the core thereof to the discs carried by the core is different than the relationship of the core 6 to the discs 7 and 10, as will be hereinafter more fully described.

In the form of my invention shown in the figures hereinbefore noted, a rigid core 11 preferably of metal is formed with an angular section, but unlike cores 4 and 6 the corresponding

sides of the incremental sections throughout the length of the core remain parallel, that is, the core 11 is untwisted. Discs 12, 13 and 14 are mounted upon the core 11, said discs having peripheral scallops 15, similar to the scallops 3 hereinbefore described. However, it will be noted that the discs 12, 13 and 14 differ from one another in that the central apertures 16, 17 and 18 respectively provided in discs 12, 13 and 14 are angularly displaced relative to each other and relative to the scallops 15. Consequently, when the discs 12, 13 and 14 are threaded upon core 11 the scallops define a plurality of partial helices, or complete helices depending upon the number of discs employed.

The discs 12, 13 and 14 may be arranged in groups 19 interposed with groups 20 of discs 21 having circular peripheries, such as described in the form of my invention shown in Fig. 7 or the entire roll may comprise discs 12, 13 and 14 in which case the periphery of the roll will resemble the roll 2.

It is to be understood that in all forms of my invention the surface helices may be continuous or discontinuous. Also the pitch of the helices may be changed to suit the purpose for which the roll is to be used. In the form of my invention shown in Figs. 1, 2 and 7, the pitch of the surface helices may be changed by the number of complete twists which may be imparted to the cores 4 and 6. The number of helices formed upon the surface of the rolls will depend primarily upon the number of scallops 3 provided upon the periphery of the individual discs 1 and 7. This latter condition is also true with respect to the form of my invention illustrated in Figs. 3, 4, 5 and 6.

The pitch of the continuous or discontinuous surface helices in a roll constructed after the teaching of Figs. 3, 4, 5 and 6, will depend upon the angular displacement of the apertures 16, 17 and 18 with respect to each other. Of course, if the scallops 15 repeat themselves in symmetrical fashion throughout the circumference of the discs 12, 13 and 14, the angular relationship between the apertures 16, 17 and 18 changes only throughout the arc included between an adjacent pair of scallops. Thereafter, the design repeats itself.

In illustrating and describing the discontinuous helical surfaced roll, three scalloped discs constitute the groups 8 and 19 interposed with three circular discs constituting the groups 9 and 20. Of course, the respective groups 8, 9, 19 and 20 may be formed of any number of discs, and further the relative thicknesses of the various discs constituting the respective groups may be the same or different, as desired.

Another important feature of my invention resides in the peripheral surface formation of all of the scalloped discs herein described. It will be noted that in all cases, the diameter of the discs at one face thereof is greater than the diameter of said disc at the other face thereof, that is, the peripheral surfaces of the discs are chamfered or of generally frusto-conical shape. Also, it will be noted that when the discs are assembled upon the core, the smaller diameter face of each disc abuts against the larger diameter face of its neighboring disc. Accordingly, when axial pressure is applied to the stack of discs carried upon a core, and said discs are locked under the applied pressure, radial expansion of the discs takes place, but such expansion occurs to a greater degree along the greater diameter face than along the face of

lesser diameter of each disc; as a result, the roll surface is characterized by having a plurality of circumferentially aligned, axially spaced relatively soft resilient tongues which greatly increase the effective purchase which the rolls obtain upon the corn husk.

A difficulty which is frequently encountered in corn husking machines of this general type wherein two juxtaposed rotating husking rolls form a nip through which the corn to be husked moves axially parallel to the rolls during the husking operation, resides in the phenomena that many of the ears of corn move through the nip without rotating and, hence, only the husk on one side of the ear is removed. By the provision of the soft, resilient tongues carried by the rolls, as hereinbefore described, this difficulty is eliminated and the ears are caused to rotate in the nip as they progress axially therethrough. Hence, the entire husk is removed from all of the ears.

It is apparent that herein is provided a roll which is particularly adapted for the husking of corn, but it is not to be limited to this specific use, since, it may be used for other purposes. It is intended that the present invention be directed to a roll construction broadly wherever, and in whatever environment said roll may find advantageous use.

I claim as my invention:

A corn husking roll comprising a rigid, elongated central core of angular cross-section, a plurality of relatively flexible, resilient discs carried by said core in face to face relationship, each of said discs being provided with a central aperture conforming in shape and substantially in size to the cross-section of said core, said discs being disposed upon said core in alternate groups, the discs comprising one group being substantially circular and being provided with a plurality of substantially equally spaced peripheral scallops, the diameter across one face of each of said scalloped discs being greater than the diameter across the opposite face of said disc, said discs being mounted upon said core with the larger diameter face of each disc in pressure contact with the smaller diameter face of an adjacent disc, corresponding scallops upon adjacent discs comprising said group being angularly offset progressively different degrees with respect to a predetermined defining side of the angular central aperture whereby the scallops on adjacent discs of said group define a portion of a helix on the roll periphery and the discs act successively in engaging and pulling husks from an ear of corn and in moving the ear axially of the roll, and the peripheries of the discs comprising the remaining group being substantially circular and of a diameter less than the diameter of the discs comprising the first-mentioned group.
